CARL ROBERT TESCH AND CARL CHRIST. FRANK, OF LEIPSIC, SAXONY,
GERMANY.

HORSE-COLLAR.

SPECIFICATION forming part of Letters Patent No. 296,250, dated April 1, 1884.

Application filed July 1, 1882. (No model.) Patented in Germany August 17, 1880, No. 13,867, and February 1, 1881, No. 15,962; in Austria April 10, 1881, No. 6,753, and October 19, 1881, No. 28,760; in France April 19, 1881, No. 111,230; in Belgium September 12, 1881, No. 55,713, and in Italy May 26, 1882, No. 14,231.

To all whom it may concern:

Be it known that we, CARL ROBERT TESCH and CARL CHRIST. FRANK, citizens of Germany, residing at Leipsic, Saxony, in the Empire of Germany, have invented new and useful Improvements in Horse-Collars, of which the following is a specification.

Our invention consists in peculiar shaped and connected metal frames forming the collar; second, in the arrangement for varying the length and width of the collar; third, in the removable cushion; fourth, in the construction of the lock or fastening device; and, fifth, in the attachment of the trace hooks or rings.

In the accompanying drawings, Figure I represents a front view of our improved horse-collar. Fig. II is a side view of the same. The remaining twenty-two figures are detail views of various parts, referred to in the following specification.

Similar letters represent similar parts in all the figures.

The main plates or frames A, forming the horse-collar body, are hollowed out or recessed, in which the plates B are arranged. These plates B are at their upper ends, near the head of the collar, corrugated or provided with regular projections or teeth b, (see Figs. III, VII, VIII, and IX,) and the plates B, as well as the frames A, have suitable slots, a, Figs. IV, V, IX, through which the bolt d of the rein-rings C passes freely. Inside of the plates B plates D are arranged, the lower ends of which are provided with projections or teeth corresponding with and meshing into the projections or teeth b at the ends of the plate B, and arranged at their upper ends with suitable lugs, h, fitting together and forming a hinge-joint, Figs. I, III, IV, V, and VII, through which the pin f passes to fasten the same together. (See Fig. XXI.) To this pin f a lever or upright stand, g, Fig. I, II, XXI, and XXII, is attached, to which bells or any other desired ornament may be attached.

Near the lugs h a guiding-plate, F, capable of sliding against the outside of the frame A, is attached and firmly fastened.

To the inner end of the plate D, which is

provided with the teeth fitting into the teeth 50 of the plate B, the bolt d is firmly attached, passing through the slots a in the plate B, frame A, and guiding-plate F, and to which the hub k of the rein-ring C is screwed. The screwing down of the hub k will force the teeth 55 on the end of the plate D tight into the teeth in the plate B, and thus prevent any moving of these parts. By changing the position of the end of the plate D in regard to the end of the plate B the length of the horse-collar 60 may be increased or diminished, as may be required to suit the neck of the horse.

Instead of making corrugations, suitable projections, or teeth on the plate B, the same may be made in the frame A, and the corresponding teeth, &c., in the end of the plate D made to fit into the same. Instead of these teeth in the plate D meshing into corresponding teeth in the plate B or frame A, teeth similar to a rack may be arranged in the plate 70 B, into which a pinion, n, attached to a suitable bolt at the end of the rein-ring hub k, is made to work. (See Figs. VIII, IX, X, and XI.)

To prevent the hub k from turning, a small 75 pin, i, is put through the hub k, and bolt d, Figs. VII, XXIV, and XI; or the end of this hub may be provided with teeth 3, into which a spring-pawl, 2, Figs. III, IV, works.

On the outside of the guiding-plate F a suitable scale, S, either lettered or numbered, Figs. II, IV, is engraved, to regulate and guide the size or length of the collar. Besides this arrangement for regulating the length of the collar, the width of the collar may be regulated 85 by the locking device or joint at the lower end of the collar. This locking device is shown in the drawings in Figs. XVII, XVIII, XIX, and XX. To the plate B on one side a bar, E, provided with teeth e, is attached, and to the plate B, on the other side of the collar, a bar, E', having a hub or boss, G, at its end, is attached, through which the bar E can pass. In this hub G a bolt or key, l, is fitted, attached to a rod, m, said bolt l fitting into the 95 notch or tooth on the bar E. The rod m is attached to a knob, p, acted upon by a suitable spiral spring, q, arranged in the hub G, so as

to hold the bolt *l* in the desired notch or tooth on the bar *E*. By changing the position of the bolt *l* from one notch or tooth in the bar *E* into any other tooth the width of the horse-collar may be increased or reduced, as may be required. Instead of this described locking device, a bar, *T*, provided with a number of holes, *r r*, may be attached to one of the bars *B* and attached to the other bar *B* by means of a bolt, *Z*, whereby according to the hole *r* in the bar *T* with which the connection is made the width of the collar may be increased or diminished. This arrangement is represented in Figs. XII and XIII.

15 The arrangement of attaching the draft hooks or rings to the collar is shown in Figs. XIV, XV, and XVI. A frame, *M*, is securely attached to the frame *A*, provided with three or more square holes, *u*, into which the hook-bolt *Z* is fitted and secured therein by a suitable pin, *a*. Through the head of this hook-bolt *Z* the draft-ring *W* passes. By this arrangement the position of the hook-bolt *Z* and draft-ring *W* is easily raised or lowered, as may be desired.

20 The collar-pad *P*, Fig. XXIII, is attached to the inside of the collar-frame by means of pins or bolts *r*, passing through the frame *A* and plate *B* into suitable nuts, *x*, fixed permanently to the collar-pad *P*. By this arrangement the pad is easily attached and detached or may be changed whenever desired.

25 What we claim as our invention, and desire to secure by Letters Patent, is—

35 1. In combination with the frame *A* and

plate *B*, the plates *D*, provided with lugs *h*, at one end and suitable teeth or projections at the other end engaging with corresponding teeth, *b*, made in the frame *A* or plates *B*, the bolt *d*, and the rein-ring hub *k*, arranged to 40 operate in the manner and for the purpose substantially as described.

2. In combination with the plates *B*, the bar *E*, provided with teeth *e*, and the bar *E'*, with hub *G*, bolt *l*, rod *m*, spring *q*, and head 45 or knob *p*, arranged to operate in the manner and for the purpose substantially as specified.

3. In combination with the frame *A* and plate *B*, the frame *M*, provided with three or more holes, *u*, the hook-bolt *Z*, and the draft-ring *W*, substantially as and for the purpose 50 set forth.

4. In combination with the frame *A* of a horse-collar, recessed and strengthened by plates *B*, the plates *D*, with outside guiding plates, *F*, bolt *d*, lugs *h* for rein-rings, plates *E* and *E'*, bolt *l*, frame *M*, hook-bolt *Z*, and draft-rings *W*, the whole being constructed and arranged to operate substantially in the manner and for the purpose herein described. 55

In testimony that we claim the foregoing we have hereunto set our hands this 10th day of August, A. D. 1881.

CARL ROBERT TESCH.
CARL CHRIST. FRANK.

Correction in Letters Patent No. 296,250.

It is hereby certified that in Letters Patent No. 296,250, granted April 1, 1884, upon the application of Carl Robert Jesch and Carl Christ. Frank, of Leipsic, Saxony, Germany, for an improvement in "Horse-Collars," the name of one of the patentees was erroneously written and printed "Carl Robert Tesch," instead of *Carl Robert Jesch*; and that the proper correction has been made in the files and records pertaining to the case in the Patent Office, and should be read in the Letters Patent to make it conform thereto.

Signed, countersigned, and sealed this 8th day of April, A. D. 1884.

[SEAL.]

M. L. JOSLYN,
Acting Secretary of the Interior.

Countersigned:

BENJ. BUTTERWORTH,
Commissioner of Patents.
